[57] CLAIM

An ornamental design for a guitar head, substantially as shown and described.

DESCRIPTION

FIG. 1 is a front, partial top and partial right side perspective view of a guitar head showing my new design; FIG. 2 is a left side elevational view; FIG. 3 is a front elevational view; FIG. 4 is a right side elevational view; FIG. 5 is a rear elevational view; FIG. 6 is a bottom plan view; and FIG. 7 is a top plan view.

The characteristic feature of my design is the configuration of the guitar head without the hardware.

FIG. 5.

FIG. 7.

FIG. 6.
